US00D600746S

(12) United States Design Patent
Kudimi

(10) Patent No.: US D600,746 S
(45) Date of Patent:  Sep. 22, 2009

(54) DAILY MASTER AVIATOR DISPATCH SCHEDULE AND TIME TRACKER

(76) Inventor: Eric Kudimi, 4201 N. Main St., Suite 262, Fort Worth, TX (US) 76106-2749

() Term: 14 Years

(21) Appl. No.: 29/269,259

(22) Filed: Nov. 27, 2006

(51) LOC (9) Cl. 19-01
(52) U.S. Cl. D19/1
(58) Field of Classification Search D19/1-34;
40/107, 120, 124.01-124.15, 726; 229/72;
229/92, 92.1, 300-303; 283/72, 74, 75, 103;
283/105, 106; 206/449; D21/385; D20/10

See application file for complete search history

(56) References Cited

U.S. PATENT DOCUMENTS

D313,428	S	*	1/1991	Drexler	.....	D19/9
D351,414	S	*	10/1994	Buhner	.....	D19/20
D360,896	S	*	8/1995	Buhner	.....	D19/20
D411,572	S	*	6/1999	Lord et al.	.....	D19/33
D411,573	S	*	6/1999	Carey et al.	.....	D19/33
D411,574	S	*	6/1999	Lord et al.	.....	D19/33
D415,523	S	*	10/1999	Finch et al.	.....	D19/33
D415,794	S	*	10/1999	Carey et al.	.....	D19/33
D416,575	S	*	11/1999	Plonski et al.	.....	D19/33
D435,862	S	*	1/2001	Maurette	.....	D19/26
D480,104	S	*	9/2003	McCormack	.....	D19/20
D480,420	S	*	10/2003	McCormack	.....	D19/20
D567,850	S	*	4/2008	Kudimi	.....	D19/26

Primary Examiner—T. Chase Nelson
Assistant Examiner—David G Muller

(57) CLAIM

The ornamental design of the daily master aviator dispatch schedule and time tracker, as shown and described.

DESCRIPTION

FIG. 1 is panel one of the front of the daily master aviator dispatch schedule and time tracker, showing my new design, shown separately for convenience of illustration;

FIG. 2 is panel two of the front of the dispatch schedule, shown separately for convenience of illustration;

FIG. 3 is panel three of the front of the dispatch schedule, shown separately for convenience of illustration;

FIG. 4 is panel one of the backside of the dispatch schedule, shown separately for convenience of illustration;

FIG. 5 is panel two of the backside of the dispatch schedule, shown separately for convenience of illustration;

FIG. 6 is panel three of the backside of the dispatch schedule, shown separately for convenience of illustration;

FIG. 7 is a greatly reduced front view of the daily master aviator dispatch schedule and time tracker, showing panels 1–3 combined to depict the entire front side of the chart; and, FIG. 8 is a greatly reduced back view of the daily master aviator dispatch schedule and time tracker, showing panels 1–3 combined to depict the entire back side of the chart.

The “Aircraft Cockpit and Globe” logo and “Crew Resource Management, the CRM Center,” trademark/service marks forming part of the claimed design are registered trademark/service marks belonging to Dr. Eric Kudimi.

* cited by examiner

1 Claim, 8 Drawing Sheets

AVIATOR FLIGHT
<table border="1"> <thead> <tr> <th>AIRCRAFT</th> <th>SIM</th> <th>GRD</th> <th>CFI</th> <th>NAME</th> <th>AIRCRAFT</th> <th>SIM</th> <th>GRD</th> <th>CFI</th> <th>NAME</th> </tr> </thead> <tbody> <tr> <td>Make</td> <td>Reg. No.</td> <td>Model</td> <td>Simulator ID. No. (Enter Sim. ID. No. Below)</td> <td>Classroom No. (Enter Classroom No. Below)</td> <td>Instructor Name (Enter CFI's Name/Initial Below)</td> <td>Student/Customer Name (Enter Student/Customer Name and Contact Phone Nos. Below)</td> <td>Make</td> <td>Reg. No.</td> <td>Model</td> <td>Simulator ID. No. (Enter Sim. ID. No. Below)</td> <td>Classroom No. (Enter Classroom No. Below)</td> <td>Instructor Name (Enter CFI's Name/Initial Below)</td> <td>Student/Customer Name (Enter Student/Customer Name and Contact Phone Nos. Below)</td> </tr> </tbody> </table>												AIRCRAFT	SIM	GRD	CFI	NAME	AIRCRAFT	SIM	GRD	CFI	NAME	Make	Reg. No.	Model	Simulator ID. No. (Enter Sim. ID. No. Below)	Classroom No. (Enter Classroom No. Below)	Instructor Name (Enter CFI's Name/Initial Below)	Student/Customer Name (Enter Student/Customer Name and Contact Phone Nos. Below)	Make	Reg. No.	Model	Simulator ID. No. (Enter Sim. ID. No. Below)	Classroom No. (Enter Classroom No. Below)	Instructor Name (Enter CFI's Name/Initial Below)	Student/Customer Name (Enter Student/Customer Name and Contact Phone Nos. Below)
AIRCRAFT	SIM	GRD	CFI	NAME	AIRCRAFT	SIM	GRD	CFI	NAME
Make	Reg. No.	Model	Simulator ID. No. (Enter Sim. ID. No. Below)	Classroom No. (Enter Classroom No. Below)	Instructor Name (Enter CFI's Name/Initial Below)	Student/Customer Name (Enter Student/Customer Name and Contact Phone Nos. Below)	Make	Reg. No.	Model	Simulator ID. No. (Enter Sim. ID. No. Below)	Classroom No. (Enter Classroom No. Below)	Instructor Name (Enter CFI's Name/Initial Below)	Student/Customer Name (Enter Student/Customer Name and Contact Phone Nos. Below)
THE DAILY MASTER AVIATOR DISPATCH SCHEDULE AND TIME TRACKER
TODAY DATE: _____
MANAGEMENT PERSONNEL NOTES: _____
FLIGHTCREW IMMEDIATE NOTIFICATION: _____
LOCAL WEATHER REPORT & NOTAM'S: _____
GENERAL INSTRUCTIONS:
1. Draw a horizontal line at the end of the requested schedule period across the columns.
2. Dispatcher must track and monitor aircraft flighttime and notify maintenance manager upon aircraft due inspection.
3. All overnight flights must be approved by management personnel first before their schedules can be confirmed.
4. Actual time preceded by an asterisk such as Simulator and Ground School times are optional to track.
*CIC Conquest International Aviation Press, The CRM Center © 2007 The CRM Center Patent Pending
<table border="1"> <thead> <tr> <th>TIME</th> <th>ACTUAL TIME</th> <th>ACTUAL TIME</th> <th>ACTUAL TIME</th> <th>ACTUAL TIME</th> <th>ACTUAL TIME</th> <th>ACTUAL TIME</th> <th>ACTUAL TIME</th> <th>ACTUAL TIME</th> <th>ACTUAL TIME</th> <th>ACTUAL TIME</th> <th>ACTUAL TIME</th> </tr> </thead> <tbody> <tr> <td>06:00</td> <td></td> <td></td> <td></td> <td></td> <td></td> <td></td> <td></td> <td></td> <td></td> <td></td> <td></td> </tr> <tr> <td>06:15</td> <td></td> <td></td> <td></td> <td></td> <td></td> <td></td> <td></td> <td></td> <td></td> <td></td> <td></td> </tr> <tr> <td>06:30</td> <td></td> <td></td> <td></td> <td></td> <td></td> <td></td> <td></td> <td></td> <td></td> <td></td> <td></td> </tr> <tr> <td>06:45</td> <td></td> <td></td> <td></td> <td></td> <td></td> <td></td> <td></td> <td></td> <td></td> <td></td> <td></td> </tr> <tr> <td>07:00</td> <td></td> <td></td> <td></td> <td></td> <td></td> <td></td> <td></td> <td></td> <td></td> <td></td> <td></td> </tr> <tr> <td>07:15</td> <td></td> <td></td> <td></td> <td></td> <td></td> <td></td> <td></td> <td></td> <td></td> <td></td> <td></td> </tr> <tr> <td>07:30</td> <td></td> <td></td> <td></td> <td></td> <td></td> <td></td> <td></td> <td></td> <td></td> <td></td> <td></td> </tr> <tr> <td>07:45</td> <td></td> <td></td> <td></td> <td></td> <td></td> <td></td> <td></td> <td></td> <td></td> <td></td> <td></td> </tr> <tr> <td>08:00</td> <td></td> <td></td> <td></td> <td></td> <td></td> <td></td> <td></td> <td></td> <td></td> <td></td> <td></td> </tr> <tr> <td>08:15</td> <td></td> <td></td> <td></td> <td></td> <td></td> <td></td> <td></td> <td></td> <td></td> <td></td> <td></td> </tr> <tr> <td>08:30</td> <td></td> <td></td> <td></td> <td></td> <td></td> <td></td> <td></td> <td></td> <td></td> <td></td> <td></td> </tr> <tr> <td>08:45</td> <td>V</td> <td></td> <td></td> <td></td> <td></td> <td></td> <td></td> <td></td> <td></td> <td></td> <td></td> </tr> <tr> <td>09:00</td> <td></td> <td></td> <td></td> <td></td> <td></td> <td></td> <td></td> <td></td> <td></td> <td></td> <td></td> </tr> <tr> <td>09:15</td> <td></td> <td></td> <td></td> <td></td> <td></td> <td></td> <td></td> <td></td> <td></td> <td></td> <td></td> </tr> <tr> <td>09:30</td> <td></td> <td></td> <td></td> <td></td> <td></td> <td></td> <td></td> <td></td> <td></td> <td></td> <td></td> </tr> <tr> <td>09:45</td> <td>V</td> <td></td> <td></td> <td></td> <td></td> <td></td> <td></td> <td></td> <td></td> <td></td> <td></td> </tr> <tr> <td>10:00</td> <td></td> <td></td> <td></td> <td></td> <td></td> <td></td> <td></td> <td></td> <td></td> <td></td> <td></td> </tr> <tr> <td>10:15</td> <td></td> <td></td> <td></td> <td></td> <td></td> <td></td> <td></td> <td></td> <td></td> <td></td> <td></td> </tr> <tr> <td>10:30</td> <td></td> <td></td> <td></td> <td></td> <td></td> <td></td> <td></td> <td></td> <td></td> <td></td> <td></td> </tr> <tr> <td>10:45</td> <td>V</td> <td></td> <td></td> <td></td> <td></td> <td></td> <td></td> <td></td> <td></td> <td></td> <td></td> </tr> <tr> <td>11:00</td> <td></td> <td></td> <td></td> <td></td> <td></td> <td></td> <td></td> <td></td> <td></td> <td></td> <td></td> </tr> <tr> <td>11:15</td> <td></td> <td></td> <td></td> <td></td> <td></td> <td></td> <td></td> <td></td> <td></td> <td></td> <td></td> </tr> <tr> <td>11:30</td> <td></td> <td></td> <td></td> <td></td> <td></td> <td></td> <td></td> <td></td> <td></td> <td></td> <td></td> </tr> <tr> <td>11:45</td> <td>V</td> <td></td> <td></td> <td></td> <td></td> <td></td> <td></td> <td></td> <td></td> <td></td> <td></td> </tr> <tr> <td>12:00</td> <td></td> <td></td> <td></td> <td></td> <td></td> <td></td> <td></td> <td></td> <td></td> <td></td> <td></td> </tr> <tr> <td>12:15</td> <td></td> <td></td> <td></td> <td></td> <td></td> <td></td> <td></td> <td></td> <td></td> <td></td> <td></td> </tr> <tr> <td>12:30</td> <td></td> <td></td> <td></td> <td></td> <td></td> <td></td> <td></td> <td></td> <td></td> <td></td> <td></td> </tr> <tr> <td>12:45</td> <td>V</td> <td></td> <td></td> <td></td> <td></td> <td></td> <td></td> <td></td> <td></td> <td></td> <td></td> </tr> <tr> <td>13:00</td> <td></td> <td></td> <td></td> <td></td> <td></td> <td></td> <td></td> <td></td> <td></td> <td></td> <td></td> </tr> <tr> <td>13:15</td> <td></td> <td></td> <td></td> <td></td> <td></td> <td></td> <td></td> <td></td> <td></td> <td></td> <td></td> </tr> <tr> <td>13:30</td> <td></td> <td></td> <td></td> <td></td> <td></td> <td></td> <td></td> <td></td> <td></td> <td></td> <td></td> </tr> <tr> <td>13:45</td> <td>V</td> <td></td> <td></td> <td></td> <td></td> <td></td> <td></td> <td></td> <td></td> <td></td> <td></td> </tr> <tr> <td>14:00</td> <td></td> <td></td> <td></td> <td></td> <td></td> <td></td> <td></td> <td></td> <td></td> <td></td> <td></td> </tr> <tr> <td>14:15</td> <td></td> <td></td> <td></td> <td></td> <td></td> <td></td> <td></td> <td></td> <td></td> <td></td> <td></td> </tr> <tr> <td>14:30</td> <td></td> <td></td> <td></td> <td></td> <td></td> <td></td> <td></td> <td></td> <td></td> <td></td> <td></td> </tr> <tr> <td>14:45</td> <td>V</td> <td></td> <td></td> <td></td> <td></td> <td></td> <td></td> <td></td> <td></td> <td></td> <td></td> </tr> <tr> <td>15:00</td> <td></td> <td></td> <td></td> <td></td> <td></td> <td></td> <td></td> <td></td> <td></td> <td></td> <td></td> </tr> <tr> <td>15:15</td> <td></td> <td></td> <td></td> <td></td> <td></td> <td></td> <td></td> <td></td> <td></td> <td></td> <td></td> </tr> <tr> <td>15:30</td> <td></td> <td></td> <td></td> <td></td> <td></td> <td></td> <td></td> <td></td> <td></td> <td></td> <td></td> </tr> <tr> <td>15:45</td> <td>V</td> <td></td> <td></td> <td></td> <td></td> <td></td> <td></td> <td></td> <td></td> <td></td> <td></td> </tr> <tr> <td>16:00</td> <td></td> <td></td> <td></td> <td></td> <td></td> <td></td> <td></td> <td></td> <td></td> <td></td> <td></td> </tr> <tr> <td>16:15</td> <td></td> <td></td> <td></td> <td></td> <td></td> <td></td> <td></td> <td></td> <td></td> <td></td> <td></td> </tr> <tr> <td>16:30</td> <td></td> <td></td> <td></td> <td></td> <td></td> <td></td> <td></td> <td></td> <td></td> <td></td> <td></td> </tr> <tr> <td>16:45</td> <td>V</td> <td></td> <td></td> <td></td> <td></td> <td></td> <td></td> <td></td> <td></td> <td></td> <td></td> </tr> <tr> <td>17:00</td> <td></td> <td></td> <td></td> <td></td> <td></td> <td></td> <td></td> <td></td> <td></td> <td></td> <td></td> </tr> <tr> <td>17:15</td> <td></td> <td></td> <td></td> <td></td> <td></td> <td></td> <td></td> <td></td> <td></td> <td></td> <td></td> </tr> <tr> <td>17:30</td> <td></td> <td></td> <td></td> <td></td> <td></td> <td></td> <td></td> <td></td> <td></td> <td></td> <td></td> </tr> <tr> <td>17:45</td> <td>V</td> <td></td> <td></td> <td></td> <td></td> <td></td> <td></td> <td></td> <td></td> <td></td> <td></td> </tr> <tr> <td>18:00</td> <td></td> <td></td> <td></td> <td></td> <td></td> <td></td> <td></td> <td></td> <td></td> <td></td> <td></td> </tr> <tr> <td>18:15</td> <td></td> <td></td> <td></td> <td></td> <td></td> <td></td> <td></td> <td></td> <td></td> <td></td> <td></td> </tr> <tr> <td>18:30</td> <td></td> <td></td> <td></td> <td></td> <td></td> <td></td> <td></td> <td></td> <td></td> <td></td> <td></td> </tr> <tr> <td>18:45</td> <td>V</td> <td></td> <td></td> <td></td> <td></td> <td></td> <td></td> <td></td> <td></td> <td></td> <td></td> </tr> <tr> <td>19:00</td> <td></td> <td></td> <td></td> <td></td> <td></td> <td></td> <td></td> <td></td> <td></td> <td></td> <td></td> </tr> <tr> <td>19:15</td> <td></td> <td></td> <td></td> <td></td> <td></td> <td></td> <td></td> <td></td> <td></td> <td></td> <td></td> </tr> <tr> <td>19:30</td> <td></td> <td></td> <td></td> <td></td> <td></td> <td></td> <td></td> <td></td> <td></td> <td></td> <td></td> </tr> <tr> <td>19:45</td> <td>V</td> <td></td> <td></td> <td></td> <td></td> <td></td> <td></td> <td></td> <td></td> <td></td> <td></td> </tr> <tr> <td>20:00</td> <td></td> <td></td> <td></td> <td></td> <td></td> <td></td> <td></td> <td></td> <td></td> <td></td> <td></td> </tr> <tr> <td>20:15</td> <td></td> <td></td> <td></td> <td></td> <td></td> <td></td> <td></td> <td></td> <td></td> <td></td> <td></td> </tr> <tr> <td>20:30</td> <td></td> <td></td> <td></td> <td></td> <td></td> <td></td> <td></td> <td></td> <td></td> <td></td> <td></td> </tr> <tr> <td>20:45</td> <td>V</td> <td></td> <td></td> <td></td> <td></td> <td></td> <td></td> <td></td> <td></td> <td></td> <td></td> </tr> <tr> <td>OVER</td> <td></td> <td></td> <td></td> <td></td> <td></td> <td></td> <td></td> <td></td> <td></td> <td></td> <td></td> </tr> <tr> <td>NIGHT</td> <td></td> <td></td> <td></td> <td></td> <td></td> <td></td> <td></td> <td></td> <td></td> <td></td> <td></td> </tr> <tr> <td></td> <td></td> <td></td> <td></td> <td></td> <td></td> <td></td> <td></td> <td></td> <td></td> <td></td> <td></td> </tr> </tbody> </table>												TIME	ACTUAL TIME	ACTUAL TIME	ACTUAL TIME	ACTUAL TIME	ACTUAL TIME	ACTUAL TIME	ACTUAL TIME	ACTUAL TIME	ACTUAL TIME	ACTUAL TIME	ACTUAL TIME	06:00												06:15												06:30												06:45												07:00												07:15												07:30												07:45												08:00												08:15												08:30												08:45	V											09:00												09:15												09:30												09:45	V											10:00												10:15												10:30												10:45	V											11:00												11:15												11:30												11:45	V											12:00												12:15												12:30												12:45	V											13:00												13:15												13:30												13:45	V											14:00												14:15												14:30												14:45	V											15:00												15:15												15:30												15:45	V											16:00												16:15												16:30												16:45	V											17:00												17:15												17:30												17:45	V											18:00												18:15												18:30												18:45	V											19:00												19:15												19:30												19:45	V											20:00												20:15												20:30												20:45	V											OVER												NIGHT
TIME	ACTUAL TIME	ACTUAL TIME	ACTUAL TIME	ACTUAL TIME	ACTUAL TIME	ACTUAL TIME	ACTUAL TIME	ACTUAL TIME	ACTUAL TIME	ACTUAL TIME	ACTUAL TIME
06:00
06:15
06:30
06:45
07:00
07:15
07:30
07:45
08:00
08:15
08:30
08:45	V
09:00
09:15
09:30
09:45	V
10:00
10:15
10:30
10:45	V
11:00
11:15
11:30
11:45	V
12:00
12:15
12:30
12:45	V
13:00
13:15
13:30
13:45	V
14:00
14:15
14:30
14:45	V
15:00
15:15
15:30
15:45	V
16:00
16:15
16:30
16:45	V
17:00
17:15
17:30
17:45	V
18:00
18:15
18:30
18:45	V
19:00
19:15
19:30
19:45	V
20:00
20:15
20:30
20:45	V
OVER NIGHT
<table border="1"> <thead> <tr> <th>PAGE TOTAL</th> <th>AMOUNT BROUGHT FORWARD</th> <th>TOTAL TO DATE</th> </tr> </thead> </table>												PAGE TOTAL	AMOUNT BROUGHT FORWARD	TOTAL TO DATE
PAGE TOTAL	AMOUNT BROUGHT FORWARD	TOTAL TO DATE

Fig. 1

AND GROUND ACTIVITY DISPATCH SCHEDULE – TIME

Fig. 2

Fig. 3

Fig. 4

FUTURE PROPOSED REQUESTED SCHEDULE

Fig. 5

DATE	AIRCRAFT	SIM	GRD	CFI	NAME
(Enter Requested Date Below)
Date Reg. No. (Enter Registration No. Below)	AIRCRAFT Model	SIM	GRD	CFI	NAME
(Enter Simulator ID. No. (Enter Sim. ID. No. Below)
(Enter Classroom No. Below)
Classroom No. Instructor Name (Enter Classroom No. Below)
Instructor Name (Enter CFI Name/Initials Below)
Student/Customer Name (Enter Student/Customer Name and Contact Phone No. Below)
TIME
06:00
06:15
06:30
06:45
07:00
07:15
07:30
07:45
08:00
08:15
08:30
08:45
09:00
09:15
09:30
09:45
10:00
10:15
10:30
10:45
11:00
11:15
11:30
11:45
12:00
12:15
12:30
12:45
13:00
13:15
13:30
13:45
14:00
14:15
14:30
14:45
15:00
15:15
15:30
15:45
16:00
16:15
16:30
16:45
17:00
17:15
17:30
17:45
18:00
18:15
18:30
18:45
19:00
19:15
19:30
19:45
20:00
20:15
20:30
20:45
OVER NIGHT

Crew Resource Management
The CRM Center®

FUTURE STANDBY REQUEST NO. 1

Aircraft Make & Model _____
 Aircraft Registration No. _____
 Instructor Name _____
 From _____ To _____
 From _____ To _____
 Day Phone No. _____
 Night/Cell Phone No. _____
 E-mail _____
 Confirmation Date: _____

FUTURE STANDBY REQUEST NO. 2

Aircraft Make & Model _____
 Aircraft Registration No. _____
 Instructor Name _____
 From _____ To _____
 From _____ To _____
 Day Phone No. _____
 Night/Cell Phone No. _____
 E-mail _____
 Confirmation Date: _____

FUTURE STANDBY REQUEST NO. 3

Aircraft Make & Model _____
 Aircraft Registration No. _____
 Instructor Name _____
 From _____ To _____
 From _____ To _____
 Day Phone No. _____
 Night/Cell Phone No. _____
 E-mail _____
 Confirmation Date: _____

FUTURE STANDBY REQUEST NO. 4

Aircraft Make & Model _____
 Aircraft Registration No. _____
 Instructor Name _____
 From _____ To _____
 From _____ To _____
 Day Phone No. _____
 Night/Cell Phone No. _____
 E-mail _____
 Confirmation Date: _____

FUTURE STANDBY REQUEST NO. 5

Aircraft Make & Model _____
 Aircraft Registration No. _____
 Instructor Name _____
 From _____ To _____
 From _____ To _____
 Day Phone No. _____
 Night/Cell Phone No. _____
 E-mail _____
 Confirmation Date: _____

FUTURE STANDBY REQUEST NO. 6

Aircraft Make & Model _____
 Aircraft Registration No. _____
 Instructor Name _____
 From _____ To _____
 From _____ To _____
 Day Phone No. _____
 Night/Cell Phone No. _____
 E-mail _____
 Confirmation Date: _____

Fig. 6

Fig. 7

८८